UNITED STATES PATENT OFFICE.

SIDNEY BECKWORTH AND HERMAN F. WULLSTEIN, OF LITTLEROCK,
IOWA.

WIRE-STRETCHER.

SPECIFICATION forming part of Letters Patent No. 752,948, dated February 23, 1904.

Application filed December 19, 1903. Serial No. 185,858. (No model.)

To all whom it may concern:

Be it known that we, SIDNEY BECKWORTH and HERMAN F. WULLSTEIN, citizens of the United States, residing at Littlerock, in the county of Lyon and State of Iowa, have invented certain new and useful Improvements in Wire-Stretchers; and we do hereby declare that the following is a full, clear, and exact description of the same, reference being had to the annexed drawings, making a part of this specification, and to the letters of reference marked thereon.

The present invention has for its object to provide a simple and practical device for stretching wires for fences, telegraph, telephone, electric-light lines, or for any other purpose in which a wire-stretching device may be found useful; and it consists of a wire-stretcher constructed substantially as shown in the drawings and hereinafter described and claimed.

Figure 1 of the drawings is a side elevation of the complete wire-stretcher constructed in accordance with our invention; Fig. 2, a detail view in perspective and on an enlarged scale of one of the wire-clamps and its connections; Fig. 3, a similar view of the wire-clamp connected to the opposite side of the hand-lever to that of the former clamp; Fig. 4, a perspective view of the end of the cam-jaw; Fig. 5, a detail sectional view showing a portion of each cam-jaw and the bar to which said jaws are connected.

In the accompanying drawings, A represents a hand-lever formed with a plurality of perforations or holes *b* and notches *a*, said holes receiving a clamping-screw *c* to hold to said lever the double arms *B* of one of the wire-clamps, thereby rendering said clamp adjustable upon the lever as circumstances require, and the notches are to receive a yoke *C* upon the opposite clamp and admit of the clamp being adjusted upon the lever. The extremities of the arms *B* terminate in eyes *d*, through which the clamping-screw *c* extends, while the yoke *C* is closed and slips over the end of the lever *A* and engages one of the notches therein, the arms and yoke being shown more clearly in Figs. 2 and 3 of the

drawings. The arms *B* and the yoke *C* are each a part of the slotted bars *D* *E*, respectively, the construction of the bars being the same, the former having elongated slots *h* and the latter elongated slots *e*. The bar *D* is connected to a shank *F* by means of pins *f*, by which said bar is adjustable thereon, and the bar *E* is connected to the shank *G* by pins *g*, the pins in both instances extending through the slots in the bars and are fastened thereto and headed.

Pivoted to the bar *D* are toggle-links *H* *I*, and to the bar *E* are pivoted similar toggle-links *J* *K*, and to each pair of toggle-links are pivoted cam-jaws *L* *M* and cam-jaws *N* *O*, respectively, as shown in Figs. 2 and 3 of the drawings. The shank *F* has a curved support *h*, to which are pivoted the cam-jaws *L* *M*, and the shank *G* has a similar support *i*, to which are pivoted the cam-jaws *N* *O*, the curved supports being above the plane of the shanks, so that the slotted bars and the toggle-links will be below the plane of the cam-jaws. The cam-jaws *L* *N* are plain and of the same thickness, while the cam-jaws *M* *O* have raised guide-flanges *l* *m*, respectively, to form guides for the former jaws and guides for the wire passing between the jaws when the wire is being stretched.

It is evident that in the description of the invention many changes and modifications may be made in the several details of construction without departing from the essential features of the invention, and we therefore do not wish to limit ourselves to the precise details of construction, but leave the invention open to such changes as would come within ordinary mechanical judgment.

Having now fully described our invention, what we claim as new, and desire to secure by Letters Patent, is—

1. A wire-stretcher comprising a suitable hand-lever, two clamping devices, each adjustably and removably connected to the lever and consisting of a shank and curved support, a bar having elongated slots adjustably connected to the shank, pivoted cam-jaws upon the support, one of which has a raised guide-flange, and toggle-links pivotally connected

to the slotted bar and to the pivoted cam-jaws, substantially as and for the purpose set forth.

2. A wire-stretcher comprising a hand-lever having notches and perforations, a slotted bar 5 having double arms with eyes at their ends to embrace the lever and a set-screw engaging the eyes and the perforations in the lever, a slotted bar terminating in a yoke to engage the notches in the lever, the bar and the yoke 10 carrying each a shank having a curved support, cam-jaws pivoted thereto, toggle-links

connecting the slotted bar with the jaws, one of the jaws having a raised guide-flange, substantially as and for the purpose specified.

In testimony whereof we affix our signatures ¹⁵ in presence of two witnesses.

SIDNEY BECKWORTH.
HERMAN F. WULLSTEIN.
